CLAIM

The ornamental design for a dust collector attachment for portable electric hammer drill as shown and described.

DESCRIPTION

FIG. 1 is a front, left, and top perspective view of a dust collector attachment for portable electric hammer drill in accordance with our new design;

FIG. 2 is a rear, right, and top perspective view of the dust collector attachment for portable electric hammer drill in accordance with our new design;

FIG. 3 is a front elevational view of the dust collector attachment for portable electric hammer drill in accordance with our new design;

FIG. 4 is a rear elevational view of the dust collector attachment for portable electric hammer drill in accordance with our new design;

FIG. 5 is a top plan view of the dust collector attachment for portable electric hammer drill in accordance with our new design;

FIG. 6 is a bottom plan view of the dust collector attachment for portable electric hammer drill in accordance with our new design;

FIG. 7 is a left side elevational view of the dust collector attachment for portable electric hammer drill in accordance with our new design;

FIG. 8 is a right side elevational view of the dust collector attachment for portable electric hammer drill in accordance with our new design; and,

FIG. 9 is a front, left, and top perspective view of the dust collector attachment for portable electric hammer drill in accordance with our new design illustrating a state in which an environmental structure (a portable electric hammer drill) is attached to the dust collector attachment.

(Continued)

The broken lines in the drawings illustrate the environmental structures or portions of the dust collector attachment for portable electric hammer drill which form no part of the claimed design.

The dust case of the dust collector attachment is translucent. The oblique line shading indicates the translucent surface.
